Company, Inc., West Concord, Mass., a corporation of
Massachusetts

Filed Oct. 11, 1963, Ser. No. 76,943

Term of patent 14 years

(Cl. D52—6)

FIG. 1 is an isometric view of a radiation measuring instrument or similar article showing our new design;

FIG. 2 is a plan view;

FIG. 3 is a bottom view;

FIG. 4 is a view of the side opposite to that of FIG. 1;

FIG. 5 is an end elevation viewed from the right hand side of FIG. 1; and

FIG. 6 is an end elevation viewed from the left hand side of FIG. 1.

The dominant features of our new design reside in the full-line portion of the drawings.

We claim:

The ornamental design for a radiation measuring instrument or similar article, substantially as shown and described.
